UNITED STATES PATENT OFFICE.

JOHAN ANTON AVÉN, OF STOCKHOLM, SWEDEN, ASSIGNOR, BY MESNE ASSIGNMENTS, TO THE FIRM OF DEUTSCHE TELEPHONWERKE GESELLSCHAFT MIT BESCHRÄNKTER HAFTUNG, OF BERLIN, GERMANY.

TELEPHONE-EXCHANGE SYSTEM.

No. 851,792.

Specification of Letters Patent.

Patented April 30, 1907.

Application filed November 1, 1904. Serial No. 230,944.

To all whom it may concern:

Be it known that I, JOHAN ANTON AVÉN, a subject of the King of Sweden, residing at Stockholm, in the Kingdom of Sweden, have 5 invented new and useful Improvements in Telephone-Exchange Systems, of which the following is a specification.

My invention relates to a telephone call distributing system and is materially distinguished from the usual systems of that kind by the manner in which the work to be done is distributed.

As is well known, hitherto two operators, the so-called "distributing" and "connecting" operators have both to handle each one plug. The distributing operator upon receiving a call inserted a plug into the answering jack of the calling subscriber's line, said plug being connected with another plug 20 at the connecting board, whereafter the connecting operator answered the call of the calling subscriber and completed the connection wanted. According to my invention, however, a connection between two subscribers is effected in quite another manner. The operator who receives the call and whom I will designate as "annunciator operator" has no plug at all. At her place only annunciators, such as drops or lamps, 25 are provided and further means for communicating to the connecting operator the number of the calling subscriber. This means for communicating the number of the calling subscriber to the connecting operator may consist for instance in an order 30 circuit extending from the head set of the annunciator operator over a key to the head set of the connecting operator, or of figure indicators, pointers or the like. The connecting operator upon receiving the number 35 of the calling subscriber inserts her answering plug into the jack of the calling subscriber's line provided at her place and makes then the connection in exactly the same way as 40 in a usual telephone exchange, *i. e.* as in a telephone exchange wherein each connection is made by only one operator. From the exchange of the latter system my invention differs by the fact that the annunciators are all 45 combined in a special board and have a special operator attending the same. By this arrangement an essentially greater speed of the work is obtained, as the annunciator oper-

ator has only to attend to the line signals but not to the cut off signals and as she 55 can always select a free connecting operator for establishing the wanted connection. Furthermore, according to my invention answering jacks are fully dispensed with, the multiple jacks at the connecting board 60 serving as well for answering as for connecting.

In the accompanying drawing the subject matter of my invention is diagrammatically 65 illustrated in one form.

The subscriber stations, two of which C, D are illustrated, are connected with the multiple jacks c^1, c^2, c^3 and d^1, d^2, d^3 respectively and with the armatures of cut-off relays a, b . The lines 1 and 3 extend from one armature 70 of the corresponding cut-off relay a, b directly to one pole of the central battery z , while the other subscriber's lines 2, 4 extend to the other pole of the battery z over a line relay d and e , respectively, the line relays 75 controlling the lamps f, g . All the line signals are combined in a special board which I will designate "annunciator board," while all the jacks are combined in another special board, which I will call "connecting board." 80 Of course each subscriber's line has a jack in every section of the connecting board. The annunciator operator A is provided with the usual head set i , a plurality of keys j and a plurality of busy signals k . Each of 85 the latter is connected with one position at the connecting board and shows whether the operator at the latter position is busy or not. The cord system of the connecting operator B may be arranged in any of the 90 usual manners but has in addition a relay m and two springs n^1, n^2 in the combined listening and ringing key o . p is the head set, q the ringing machine, z' the central battery, which may be of course combined 95 with the battery z to a single one, r an impedance coil. s, s^1 are the clearing-out signals and i, t^1 the answering and connecting jack respectively. Each position at the connecting board B is further provided with two 100 relays u, v and a so-called position switch w .

The operation is as follows: If the subscriber C wants for instance to be connected with the subscriber D, he takes his receiver from its hook, whereupon the line relay d 105 attracts its armature so that the circuit of

- the line lamp f is closed. On seeing the line lamp f lighted up, the annunciator operator A presses such a key j , the lamp k of which is not lighted up and thus indicates the corresponding connecting operator B as free. The lamp k forms a part of a circuit containing the armature of the relay v of the corresponding connecting operator B. As long as the latter is not busy, her relay m has no current so that the following circuit is closed: the free pole of battery z , 5, one armature of m , 6, armature of u , v , w , ground. Therefore the armature of the relay v is attracted as long as the operator B is free. By pressing the key j the operator A connects first her head set i over the wires 7, 8 and two armatures of the relay m with the head set p of the operator B, and secondly closes the circuit of the relay u over the springs j^1 , j^2 , of her key j . The relay u attracts its armature and breaks the circuit of the relay v so that the armature of the latter falls back and closes the circuit of the lamp k , which is of course bridged to similar lamps at the other positions at the annunciator board. Hereby the operator B is indicated as busy not only at the position of the operator A but also on the other positions at the annunciator board. The operator A now tells the number of the calling subscriber C to the operator B whereupon the latter inserts the answering plug t into the jack c^1 at her position, which is connected with the calling station, inquires the number of the subscriber wanted D, makes the busy test of the line of the subscriber D and rings him up. By the insertion of the answering plug t into the jack c^1 the circuit of the cut-off relay a is closed in the usual way over the sleeve strand, so that the line lamp f extinguishes. By throwing the key o into the listening position (to the left) the springs n^1 , n^2 make contact and thus close the circuit of the relay m , which receives current on the following way: free pole of z , 5, m , n^2 , n^1 , ground. The relay m therefore attracts its three armatures and breaks thus first the connection between the two head sets i , p of the operators A and B, and secondly the connection between the wires 5 and 6. The latter arrangement has for its purpose to prevent the relay v from being excited even after the armature of the relay u has fallen back in consequence of the fact that the operator A has released her key j . When the connecting operator B leaves her place, she pulls the plug w^1 out, which is associated with the switch w , so that the latter is opened. In this manner her position is indicated as busy, though it is not occupied.
- 60 I claim:
1. In a call distributing system comprising telephone lines, each having a signaling instrument in an annunciator board and a terminal socket in each of several sections in a multiple connecting board, means at the connecting board for answering the call, testing the line of the wanted subscriber, ringing the latter up, and connecting the calling subscriber with the wanted subscriber, and means for communicating from the annunciator board to the connecting board the number of the calling subscriber; whereby a connecting operator is notified by an annunciator operator to make a connection, substantially as described.

2. In a call distributing system comprising telephone lines, each having a signaling instrument in an annunciator board and a terminal socket in each of several sections in a multiple connecting board, means at the connecting board for answering the call, testing the line of the wanted subscriber, ringing the latter up, and connecting the calling subscriber with the wanted subscriber, order wires extending from each annunciator operator to a plurality of connecting operators, and signaling circuits extending from the connecting operators to the annunciator operators; whereby a connecting operator is notified by an annunciator operator to make a connection, and the annunciator operators are apprised of the readiness of a connecting operator to make connections, substantially as described.

3. In a call distributing system comprising telephone lines, each having a signaling instrument in an annunciator board and a terminal socket in each of several sections in a multiple connecting board, means at the connecting board for answering the call, testing the line of the wanted subscriber, ringing the latter up, and connecting the calling subscriber with the wanted subscriber, order wires extending from each annunciator operator to a plurality of connecting operators, signaling circuits extending from the connecting operators to the annunciator operators, said signaling circuits containing signals and a relay at the annunciator board controlling said signals; whereby a connecting operator is notified by an annunciator operator to make a connection, and the annunciator operators are apprised of the readiness of a connecting operator to make connections, substantially as described.

4. In a call distributing system comprising telephone lines, each having a signaling instrument in an annunciator board and a terminal socket in each of several sections in a multiple connecting board, means at the connecting board for answering the call, testing the line of the wanted subscriber, ringing the latter up, and connecting the calling subscriber with the wanted subscriber, order wires extending from each annunciator operator to a plurality of connecting operators, signaling circuits extending from the connecting operators to the annunciator operators, said signaling circuits containing signals at the annunciator board and a switch

and a relay at the connecting board controlling said signals, whereby a connecting operator is notified by an annunciator operator to make a connection, and the annunciator operators are apprised of the readiness of a connecting operator to make connections, and whereby a position at the connecting board can be notified as engaged at the annunciator board if said position is not attended to by an operator.

5. In a call distributing system, comprising telephone lines, each having a signaling instrument in an annunciator board and a terminal socket in each of several sections in a multiple connecting board, means at the connecting board for answering the call, testing the line of the wanted subscriber, ringing the latter up, and connecting the calling subscriber with the wanted subscriber, order wires extending from each annunciator operator to a plurality of connecting operators, signaling circuits extending from the connecting operators to the annunciator operators, said signaling circuits containing signals at the annunciator board and being controlled by a relay, a second relay controlling the said relay and being itself controlled by the key of the annunciator operator, a third relay placed at the connecting board and controlling also the first relay and the order circuit, whereby a connecting operator is notified by an annunciator operator to make a connection, and the annunciator operators are apprised of the readiness of a connecting operator to make connections, substantially as described. 25 30 35

In testimony whereof I have signed my name to this specification in the presence of two subscribing witnesses.

JOHAN ANTON AVÉN.
